UNITED STATES PATENT OFFICE.

ALEXANDER SANDOR HECHT, OF NEW YORK, N. Y.

DESIGN FOR A RADIO LOUD-SPEAKER BASE.

Application filed August 26, 1924. Serial No. 10,558. Term of patent 3½ years.

To all whom it may concern:

Be it known that I, ALEXANDER SANDOR HECHT, a citizen of the United States, residing in the city of New York, borough of Manhattan, in the county and State of New York, have invented a new, original, and ornamental Design for Radio Loud-Speaker Bases, of which the following is a specifica-

tion, reference being had to the accompanying drawing, forming part thereof.

The figure is an elevation of a radio loud speaker base, showing my new design.

I claim:

The ornamental design for a radio loud speaker base as shown.

ALEXANDER SANDOR HECHT.
